(57) **CLAIM**

I claim the ornamental design for a pressure washer, as shown and described.

DESCRIPTION

FIG. 1 is a perspective view of the claimed design, with the pressure washer in a first orientation and with the handle in the first position;

FIG. 2 is a perspective view of the claimed design with the handle in the second position;

FIG. 3 is a perspective view of the claimed design with the pressure washer in a second orientation and the handle in the first position;

FIG. 4 is a rear view thereof;

FIG. 5 is a front view thereof;

FIG. 6 is a right side view thereof;

FIG. 7 is a left side view thereof;

FIG. 8 is a top view thereof; and,

FIG. 9 is a bottom view of the claimed design.

Any portion of the article depicted in broken lines forms no part of the claimed design.
